UNITED STATES PATENT OFFICE.

JEREMIAH F. DEARDURFF, OF FAIRFIELD, IOWA.

GABLE-DOOR.

No. 823,587.

Specification of Letters Patent.

Patented June 19, 1906.

Application filed October 20, 1905. Serial No. 283,697.

To all whom it may concern:

Be it known that I, JEREMIAH F. DEARDURFF, a citizen of the United States, and a resident of Fairfield, Jefferson county, State 5 of Iowa, have invented certain new and useful Improvements in Gable-Doors, of which the following is a specification.

The present invention relates to improvements in gable-doors, and has for its object 10 to provide a construction by which such doors may be supported close against the side of a building by means entirely protected and covered by the doors and which will cause the door to simultaneously move 15 both horizontally and vertically.

In the accompanying drawings, Figure 1 is an elevation of an embodiment of the invention, one-half of the door being shown open. Fig. 2 is a sectional view illustrating the door 20 in rear view and with both sections thereof closed. Fig. 3 is a horizontal section on the line 3 3 of Fig. 1. Fig. 4 is a section on the line 4 4 of Fig. 1. Fig. 5 is a perspective view of one of the sections of the door.

Referring to the drawings, it will be seen 25 that the door comprises two sections 1 2, each adapted to close one-half of an opening 3, formed in the wall of a building provided with an inclined roof which projects beyond or 30 overhangs said wall. Said sections are of similar form and size, each having its upper end shaped to extend into a groove or way 4, formed in the projecting section of the roof of the building when the door is in closed position. Each door-section is supported by 35 suitable means arranged between its inner face and the building-wall and adapted to cause said door to slide or move simultaneously vertically and horizontally.

In the embodiment of the invention illustrated a bell-crank lever 6 is fulcrumed on the wall in rear of and adjacent the lower end of each door-section, one arm of said lever being pivotally connected with a stud or pin 7 40 on the door and the other arm of said lever extending across the door-section and beyond the inner vertical edge thereof. The projecting end of the last said arm of the bell-crank lever 6 may be formed into a hook 8 or 45 so shaped as to serve as a handle for rocking the lever, and thereby moving the door to and from a position where it will extend across the opening 3. Each door-section is further connected with the wall adjacent the opening 50 3 by a link 9, the ends of which are respec-

tively pivoted to said wall and to a stud or pin 10 on the door. The studs or pins 7 10 are connected by a bar or rod 11, and the arms of the bell-crank 6 are connected by a tie 12. It will be seen that all of said parts 60 by which the door is supported are on the inner face or side of the door, and thereby concealed and protected by the sections 1 2.

To secure the door-sections in position to close the opening, they may be connected by 65 a hook 13 or other suitable fastening means.

To open the door when the parts are in the position shown in Fig. 2, it is merely necessary to disengage the hook 13 and lift or push upwardly on the free handle end of 70 either bell-crank lever 6. Such movement will act to rock the said lever 6 about its pivot on the stationary frame of the opening or other part of the wall, and thereby the door will be moved downward and laterally until 75 it occupies a position below and at one side of that occupied when it was extending across the opening 3. The link 9 permits the door to move as described, while maintaining it in the proper position relative to the 80 wall in which the opening 3 is formed—that is, the door will not be shifted from the vertical plane it occupies when extending across the opening 3 while moving to its open position.

It will be seen that this invention avoids 85 the necessity for employing tracks and hangers on the exterior of a building, as well as the use of special weights for counterbalancing the sliding-door sections. Each section is 90 perfectly balanced and will move easily in either direction.

When the door-sections are in position to close the opening 3, their upper ends will extend within the grooves 4 in the overhanging 95 sections of the roof, and thereby the opening will be completely and tightly closed and all of the parts by which the door is supported and moved will be completely covered and protected from the weather.

Having described my invention, what I claim as new, and desire to secure by Letters Patent, is—

The combination with a gable-wall having an opening therein, of a door or closure movable vertically and laterally to and from said opening and consisting of two independent sections, bell-crank levers fulcrumed on the wall in the space between the door and said wall, one arm of each lever having one end 100

projecting beyond the inner vertical edge of
the adjacent door-section, and the other arm
of each lever being connected to said door-
section, and links arranged in the space be-
5 tween and pivotally connected to the wall
and said door-sections, substantially as and
for the purpose described.

In testimony whereof I affix my signature
in presence of two witnesses.

JEREMIAH F. DEARDURFF.
